H. F. SHINDEL

EYE PROTECTOR

Filed March 22, 1923

Harry F. Shindel Inventor

By *W. G. McMillan*

Attorneys

UNITED STATES PATENT OFFICE.

HARRY F. SHINDEL, OF READING, PENNSYLVANIA, ASSIGNOR TO WILLSON GOGGLES INC., OF READING, PENNSYLVANIA, A CORPORATION OF PENNSYLVANIA.

EYE PROTECTOR.

Application filed March 22, 1923. Serial No. 626,892.

To all whom it may concern:

Be it known that I, HARRY F. SHINDEL, a citizen of the United States, residing at Reading, in the county of Berks and State 5 of Pennsylvania, have invented certain new and useful Improvements in Eye Protectors, of which the following is a specification.

My invention relates to goggles or eye protecting appliances which comprise removable ring-encircled lenses and connected framings therefor in which the ringed lenses are separately clampable, as indicated in Willson Patent No. 1,306,367; and my 10 particular object is to provide for loosely attaching the lens-encircling rings to their respective framings irrespective of the clamping action of the latter, as fully described in connection with the accompanying drawing, the novel features being clearly defined in the claims.

Fig. 1 is an incomplete front view of a pair of goggles embodying my invention; one of the ring-encircled lenses being shown as disengaged from its framing which is 15 only partly shown, and a part of the bridge strap being also broken away.

Fig. 2 is a cross-section on the line 2—2 of Fig. 1.

Fig. 3 is a cross-sectional view of the lens-encircling ring on the line 3—3 of Fig. 1, showing in the rear the apertured bridge-strap offset of the ring.

The lens-engaging framing indicated is made of rolled-up sheet material forming 20 an expansive eye-cup *a* with a lens-edge 25 engaging flange *f* adapted to clamp or release the removable ring-encircled lens *D*; all substantially as indicated in said Willson Patent No. 1,306,367.

Heretofore both the lens and its encircling ring have been entirely detachable 30 jointly from the framing, upon merely releasing the clamping action of the latter; and no determined relation of either to the framing has been provided for in re-engaging the ring, together with its previous 35 lens or a new one as the case may be, with the framing.

The object of my present improvement is 40 to conveniently avoid such entire detach-

ment ordinarily, and to insure a determined relation of the engaged parts. To this end I provide both the separate lens-encircling ring *b* and the clamping flange *f* of its frame, with peripheral projections forming 55 respectively a ring offset *b'*, and a frame pocket *f'* therefor, whereby the engaged ring is definitely positioned with respect to the clamping frame; and I further provide both said ring offset *b'* and said frame 60 pocket *f'* with apertures, *b*² and *f*² respectively, for the passage of the connecting bridge *h* whereby the paired frames of the completed goggles are flexibly joined in otherwise well known manner; the effect 65 being that the encircling ring of each lens will be strung upon said strip *h* so as to be yieldingly attached to its particular clamping frame even when it is released from the clamping engagement of the latter and thus 70 permit of the substitution of a new lens for instance while insuring convenient return to its proper clamping position. It will be readily understood that adjustment of the flexible bridge connection *h* to secure desired 75

spacing of the separate lens frames is effected in well known manner, as by buckle *h'* indicated in Fig. 2, and that the particular construction of the lens framings and of the lens encircling ring is immaterial excepting 80 as to the connecting means therefor particularly set forth. Entire detachment of the ring encircled lenses may be readily effected by disconnection of the bridge-strap *h* therefrom, though the latter serves ordinarily to tie the parts together when the lens-encircled rings are freed from the clamping action of the frames, and also to ensure the clamping of the parts in determined relation.

What I claim is:

1. An eye protector comprising a lens-clamping frame having a peripheral aperture, a lens-encircling ring adapted to engage said clamping frame and having a peripheral aperture adapted to register with said frame aperture, and a flexible strip engaged in said registering apertures to loosely connect said frame and ring.
2. An eye protector comprising a pair of

lens-clamping frames each having an edge-engaging flange formed with an apertured peripheral pocket, a separate lens-encircling ring for each frame flange formed with a corresponding peripheral offset apertured to register with said apertured frame pocket, and a flexible bridge strip adapted to con-

nect said apertured frame and also to loosely attach the respective apertured rings to the frames.

In testimony whereof I affix my signature.

HARRY F. SHINDEL.
